FABRIC DRYING AND SHAPING APPARATUS
AND METHOD

Frank Y. Kitzmiller, Reading, Pa.

Application August 26, 1940, Serial No. 354,152

9 Claims. (Cl. 223—76)

My invention relates to methods of, and means for, drying and shaping fabric articles, and particularly to methods and means employed in drying textile fabric articles on forms, as in the production of hosiery.

This application is a continuation, in part, of my copending applications, Serial Nos. 180,863 and 180,864, both filed December 20, 1937, and each entitled Machines for drying and shaping hosiery.

In the manufacture of fabric articles, such as stockings, on an economical, high production basis, no operation should be of extraordinary cost, or consume too much time, as has been the case in formerly drying hosiery on interiorly heated forms.

Effecting such drying on individual or single forms is extremely costly, as have been all attempts prior to my invention, so far as I am aware, to utilize a plurality of forms that are parts of one machine or apparatus, and that are moved successively with the articles into, and through, a drying chamber, and out of the chamber for removal of the articles from the forms.

Although machines of this type have been suggested, the only one known to me to have been commercially employed is substantially prohibitive in cost for general use, such machine costing almost seven times as much as the apparatus of my invention.

Such cost results from many adverse factors, such as failure to provide direct communication between a stationary heating-medium source or supply line and each movable form individually, whereby excess material and energy are required and loss sustained; the emission of proper and effective drainage for moisture of condensation in cases where such condensation forms; the inability to properly utilize the principle of superheating the air surrounding the articles on the forms and directing it back against the forms while the latter are in motion; the lack of such balance and effective arrangement of the moving elements as to require the parts to be excessive in number and weight; the improper spacing and angular positioning of the forms whereby placing and removing the articles are rendered troublesome; the arrangement of the parts rendering them difficult to assemble, repair, replace, and to remain in effective cooperation with each other; the selection of materials employed whereby faults occur from this cause; and the presence of the above and other features, which severally and in combination have precluded the production of effective, durable, economical apparatus.

Hosiery articles are of various sizes, such as full length and half hose, and are of various fabric weights, from delicate light weight two and three thread knitted silk fabrics to relatively heavy fabrics, such as Terry cloth.

As a result of this fact, in a drying and shaping machine having movable forms, the rate of movement of the forms should be according to the weight of the fabric within the range allowing for effectively placing the articles on, and removing them from, the forms, and the amount of heat supplied should also be adjustable.

A casing for a relatively large machine should be constructed from the various considerations of effective cooperation with the other parts, be as light in weight as possible, consistent with stability, be constructed for ready shipment and assembly, be of easy repair, and have other features, such as conducing to economy, neatness of appearance, and access to the apparatus enclosed thereby.

Among the objects of my invention are to provide a method of, and means for, directing a form heating medium or fluid individually to each of a plurality of moving forms from a source or distributor common thereto, and where desired and depending upon the medium employed, to return the same to a collector that is also common to the movable forms, whereby to conserve, and prevent loss of, energy or heat, to reduce the number, complexity and weight of the parts, to lower the cost of the apparatus, to render the method and apparatus more effective than former methods and apparatus, and to cause the invention to be an improvement generally in its field.

Another object of the invention is, in a method and apparatus of the above-indicated character wherein the forms are moved during drying and forming, to provide effective means for superheating the air of a drying chamber, through which the forms travel, and to maintain predetermined control over the direction and manner of flow of the superheated air, and of the points of its application to the fabrics.

Another object of the invention is, in apparatus employing a fluid, such as steam, and having a system or means for transmitting the fluid from a central source to the movable forms, and for disposing of the fluid residue, after use, as in returning it to a collector, to so render such means capable of draining the moisture of condensation from the system as to render the apparatus very much more effective, and to reduce the number, cost and weight of the parts.

Another object of the invention is to provide

casing means of light weight consistent with stability, few parts of ready stacking or packing for shipment, ready assembly and repair, compactness and neatness of appearance, ready access to enclosed parts, and effective operation, and to provide baffle means of like character for the interior of the casing.

Another object of the invention is to provide drying and forming apparatus of simple and durable construction, economical manufacture, and effective operation.

With such objects in view, as well as other advantages which may be incident to a utilization of the improvements, the invention comprises the parts and combinations thereof hereinafter set forth in the drawings, specification and claims, with the understanding that the several necessary elements constituting the same may be varied in proportion, arrangement and texture, without departing from the nature and scope of the invention.

In order to make the invention more clearly understood, means are shown in the accompanying drawings for carrying the same into practical effect, without limiting the improvements in the useful applications thereof to the particular constructions, which for the purpose of explanation are made the subject of illustration.

In the drawings:

Figure 1 is a view, in front elevation, of apparatus constructed in accordance with the example of the invention given;

Fig. 2 is a view, taken in the direction of Fig. 1, generally in about the vertical central plane section of the apparatus thereof, but having elements closer to the observer than such plane, certain parts being omitted, and others broken away;

Fig. 3 is a view, generally in top plan, of the device of Figs. 1 and 2, parts also being broken away and omitted;

Fig. 4 is a detail view, on an enlarged scale, taken generally along the line 4—4 of Fig. 3, illustrating a superheater embodied in one form of the invention;

Fig. 5 is a detail view, on an enlarged scale, taken generally along the line 5—5 of Fig. 3, of one of a plurality of arms for attachment to a distributor, and for supporting a hosiery form, only a portion of which form is shown in this figure, and portions being broken away to show conduits therein;

Fig. 6 is a view, taken substantially along the line 6—6 of Fig. 7, and also constituting a greatly enlarged view of structure, somewhat as viewed at the lower central portion of Fig. 2, but showing elements more in detail, and including elements omitted in Fig. 2;

Fig. 7 is generally a top plan view of the structure of Fig. 6, parts being broken away, and parts being omitted; and

Fig. 8 is a detail sectional view, taken substantially along the line 8—8 of Fig. 7.

Referring to the drawings, the apparatus comprises, in general, a stationary superstructure S, a casing C enclosing the superstructure S, a movable structure or carriage M on the structure S, a drive mechanism D for the carriage M, a form heat control structure G, a form arm and form structure N on the carriage M, and superheater means H.

The superstructure

The main stationary support or superstructure S, see particularly Figs. 2, 6 and 7, comprises a relatively small central metal table top or plat-

form 15 which, as shown, is of rectangular thin plate form having a depending perimetral flange, and disposed above a floor 16 on which it is mounted, as by leg members 17 joined by side braces 20.

The table top 15 is provided with an upright tubular main stationary bearing portion 18 and bosses 19, and supports brackets 23, and a motor mounting 24, for purposes to be set forth.

A generally rectangular metal framework F is mounted on the table 15, and comprises upper and lower horizontal channel beams 21 and 22, respectively, and upright side channel beams 25 joined to the horizontal beams, as through gusset plates 26. The upper horizontal beam 21 is a single continuous beam, and the beam 22 is in two lengths projecting from the table top 15.

Channel beams 27, Fig. 2, extend at angles to the floor 16, each connected to one of the leg members 17, at one end, and to one of the upright channel beams 25, at the other end.

Elements 30, as shown in Fig. 2, connect the casing C to the top of the superstructure S, and light channel beam structures 31 extend downwardly and forwardly from the central upper beam 21 to the rear side of the front panel of the casing C for bracing the latter.

In the superstructure S, it is to be noted that parts on the table 15, although of considerable lateral expanse, are mounted on this comparatively small central support, thereby greatly facilitating assembly, and rendering it unnecessary to lay out or provide widely spaced anchorages or other elements on the floor 16.

The casing

The casing C, as shown in Figs. 1, 2 and 3, is of the knockdown type, constructed chiefly of thin flat metal sheet elements or panels, including a set of four like panels 32, a pair of like panels 35, and a single forward panel 36 in the top or cover, and a set of four like panels 37, a pair of like panels 40 and 41, and a single front panel 42 in the side wall, which rests on the floor 16, each of these panels having edge flanges 45 by which it is connected, as by screws or other means, to the adjacent edge flanges of the next panels.

The casing, although made up of flat panel sides, and of polygonal horizontal cross sectional contour, conforms, in general, to the annular path of movement of a series of forms to be hereinafter set forth.

In the casing, a group of baffle plates or partitions P has the baffles arranged generally parallel to the polygonal side panels of the casing to therewith provide a passageway 46 from a front entrance 50, about the baffles, to a front exit 51 in the panel 42. About midway between the entrance 50 and the exit 51, in the aforementioned passageway at the rear of the casing, a pair of baffles 51 of the group P have adjacent edges spaced from each other to provide a passageway 52 from the passageway 46 to a space 55 within, or encompassed by, the baffle group P.

The front panel 42 supports a mirror 56, and has a horizontal apron 57, and small baffles 60 partly closing the entrance 50 and the exit 51. The baffles 60 allow space for the passage of the leg portions of the forms, and are cut away or sloped at the tops to clear the outwardly protruding upper end foot portions of each form, whereby to reduce the areas of the entrance and exit, and to prevent undue escape of heat from the casing.

A section 61 bows outwardly from the front panel 42 to encompass the forms at the bases thereof, and is provided, at its front side, with a layoff table R. The latter has legs 65, a compartment 67 for wet stockings for placing on the forms, and a platform 70 for dry stockings taken from the forms. A door 71, having a handle 72, hinges 75, and an aperture 76, is provided in the front panel under the layoff table R for providing access to parts in the lower central part of the casing.

The carriage

The movable structure or carriage M, as seen in Figs. 2, 3, 6 and 7, comprises a turntable 80 of metal, such as aluminum, and of annular form having a depending central hollow cylindrical bearing portion 81 mounted on an anti-friction or ball thrust bearing 82 in the top of the stationary bearing 18. The table 80 also has a depending outer peripheral flange 83, which rides on rollers 86 carried by plungers 87 that are vertically adjustably supported in portions 90 of the brackets 23, as by screws 91 at each corner of the stationary table 15.

The drive mechanism

To the underside of the turntable 80 is secured an internal gear wheel 92, which engages a pinion 93 keyed to a shaft 95, Fig. 7, mounted in a support 96 projecting from a housing member 97. A gear wheel 100, also secured to the shaft 95, engages a pinion 101 keyed to a shaft 102 journaled in a portion 105 of the housing 97, which also carries a worm gear wheel 106 inside the housing 97. The latter has a bottom portion 107 fixed to the bosses 19.

The worm gear wheel 106 engages a worm screw 110 in the housing 97 on a shaft 112 which, as better seen in Fig. 7, carries a pulley 115 that is connected, by a belt 116, to a speed-change pulley 117 on a shaft 120 of a motor 121. The latter is slidably mounted on the motor mounting 24 for adjustment of the speed of the pulley 117 by a screw 122 having a handle 125, which is accessible through the opening 76 in the front door 71 of the casing C. The motor 121 is controlled by a foot switch 126 under the layoff table R, as indicated in Fig. 1.

The form heat control structure

The form heat control structure G comprises a drum E, as of cast aluminum, secured, as by screws 130, to the top of the turntable 80, and provided with a cylindrical or band-like outer peripheral wall 131, upper and lower end closure walls 132 and 133, respectively, and an intermediate wall 135 sloping inwardly and downwardly from the peripheral wall 131, and provided with a small central drain aperture 136. The walls 132, 135 and 133 are joined inwardly of the drum perimeter by bosses 138.

The walls 131, 132 and 135 provide, or constitute a distributor or chamber K for a form-heating medium or fluid, such as steam, and the walls 131, 135 and 133 provide a collector or chamber L for the steam or residue therefrom, after it has heated the forms.

The top wall 132 has an inlet portion 137, in which is disposed a short tube 140 surrounded by a packing gland, including packing elements 141, a member 142 for compressing the elements 141, and a nut 145 for adjusting the member 142.

The bottom wall 133 has an outlet portion 146 communicating with, and fixed to, a tube 147 that extends through the movable and station-

ary bearing portions 81 and 18, respectively, and through a packing device J below the stationary table top 15.

The device J comprises a stationary member 150 secured to the table top 15, packing elements 151, a member 152 for holding the elements 151 from the bottom, a member 155 for compressing the elements 151 from the top, and a nut 154 for adjusting the member 155.

5 A tubular T-connector 156 provides communication from the tube 147, through a thermo-couple tube 157, a strainer 160 and a trap 161, to a drain line 164 that is adapted, as by connection to a vacuum pump, to draw the heating-medium fluid through the apparatus.

10 The T-connector 156 also connects to pipe lines 162 and 163, from superheater means to be set forth, or an elbow may be employed to connect the tube 147 to the thermo-couple tube 157 and the trap 161, and the lines 162 and 163 be connected directly to the drain line 164.

15 The thermo-couple tube 157 is connected, by conductors in a flexible conduit 165, to a thermometer T on the panel 41, as indicated in Figs. 1 and 3.

20 A tube 166, secured to the movable bearing portion 81 therein, as by a set screw 167, occupies a substantial length of each of the bearing portions 81 and 18 to provide vertical bearing surface and to lend lateral rigidity to the structure having small horizontal or thrust bearing area in the bearing 82.

The form arm and form structure

25 The form arm and form structure N comprises, in this instance, eighteen arms 170, each having a form 171 thereon, and arranged equidistantly in annular spaced series relation to each other about the drum E.

30 The latter therefore, constitutes substantially a hub or hub-like element of a structure of spider formation, of which the arms 170 and the forms 171 constitute the legs or arms.

35 Small rectangular panel or block-like lower end bases 172 on the forms 171 are secured, as by screws 174, to similar bases 173 at the outer ends of the arms.

40 All of the blocks 172 are indicated in Fig. 3, with only five each of the arms and forms shown in full outline in this figure, two of the arms indicated in Fig. 2, and only one of the arms, which are identical, showing in detail in each of Figs. 5, 6, 7 and 8.

45 As indicated in Fig. 6, the distributor K has outlet apertures 175 for the arms 170, only one of the latter being shown, and inlet apertures 176 from the arms 170. The apertures 175 and 176, only two each of which are shown in Fig. 6, are arranged about the drum, one each for each arm.

50 The arm 170 is constructed of metal, such as aluminum, having metal tubes 180 and 181, as of copper, cast therein, this feature not being germane to this application, but being the subject 55 of a separate invention. However, in other aspects, as herein claimed, the arm is germane to the invention hereof, in combination with other elements, such that the arm body itself, or the tubes 180 and 181 therein, slope upwardly and outwardly from the drum E to the arm bases 173 whereby the tubes are constituted not only as transmission means for the heating medium, such as steam, but as drain means for moisture of condensation in the arms and forms.

60 75 As shown, each arm is of hollow section, for

strength, tapering from relatively large cross section adjacent to the drum E, to smaller cross section adjacent to the base 173, having a three-point or three-screw attachment portion 182 for connection to the drum, with the tubes 180 and 181 in register with the apertures 175 and 176, respectively, and sealed, as by a gasket 185.

Near the drum E, the arm has flat-plane bottom side webs resting on the turntable 80, and apertured or slotted bosses 186 on the webs through which bolts 187 extend for adjustably securing the arm to the table. The tubes 180 and 181, which are disposed one above the other, diverge laterally, as seen in Fig. 7, to positions of register with upright tube sections 190 and 191, respectively, in the form 171.

The form 171 thereby constitutes substantially an extension of the arm 170, having attachment at only one end, namely the inner end, whereby either the form or the arm, or the form and the arm as a unit, may be dismounted, without effecting any disconnections at the outer end of the unit, or disturbing the other arms or connections between the arms outwardly from the inner ends thereof.

The forms 171 shown are for receiving half hose, although forms for receiving full length hose, and hosiery of various shapes may be substituted therefor.

The tube sections 190 and 191 are joined at the upper ends 189 thereof, thereby, with the tubes 180 and 181, forming a closed loop, or individual path, for the heating medium, from the distributor K to the form, and back to the collector L, thus rendering this path of the shortest possible length, avoiding heating of unnecessary elements, conserving heat and energy, reducing the number, weight and cost of the parts, facilitating assembly and repair, and having other advantages.

Also, the forms are arranged whereby an operator may freely work on one, by running her hands and arms up and down between the forms, without contact with, or burning from, another form or elements between the forms, in ordinary free movements, and is put to no extra care in accomplishing this result.

In this instance, steam is the heating medium, which is supplied through an inlet pipe 196, a valve 197, a horizontal pipe section 200, and a vertical pipe section 201, to the short tube 140 on the drum E.

Superheater means

Although, as indicated above, the apparatus, as described so far, may be sufficient for drying and forming fabrics of certain weights, it is desirable, in drying certain heavier fabrics, to add to the structure set forth, to the extent of the superheater means H.

Such means, as better seen in Figs. 1, 3 and 4, comprises, in this instance, two substantially identical units H disposed adjacent to the entrance 50 and the exit 51 on the panels 40 and 41, respectively.

Each unit H comprises an open-sided box-like structure 205 secured in position inside the casting C in register with an opening in the panel 40 or 41, and surrounding a radiator structure V comprising upper and lower manifolds 206 and 207, respectively, connected by parallel tubes 210, each surrounded by radiating fins 211.

The upper or inlet manifold 206 is connected, through a valve 208 and a pipe 212 to a T-connector 215 joining it to the horizontal main 75

steam inlet tube 200 through another T-connector 216, and the lower or outlet manifold 207 of the left hand superheater unit H is connected by a pipe 220 to the conduit 162, while the lower or outlet manifold of the right hand unit H, as viewed in Figs. 1 and 3, is connected, as by a pipe 221, to the conduit 163.

Each unit H further comprises a conduit 225 of relatively large diameter extending, from an open inner end 226 in the space 55 encompassed by the baffles P, to an enclosed fan or blower device 227 operated by a motor 230 mounted on a bracket 229 and adapted for drawing the warm air from the space 55, as indicated by arrows A, and directing it, as indicated by arrows B, through a flared entrance box portion 228 and the radiator V against the forms 171 as they are moved successively past the superheater. A switch 233 may be mounted on the motor 230, or elsewhere, 20 for controlling the motor circuit.

Radially inwardly of the forms, at a position opposite each blower 227, a baffle 234 of the group P is provided with a flat section 232 near the adjacent entrance or exit 50 or 51, and a curved section 235 for deflecting the draft of superheated air toward the rear of the casing, also indicated by the arrows B.

The valves 209 in the pipes 212, respectively, and the switches 233 in the circuits of the motors 30 230, may be operated to control the units H to operate severally, together, or not at all.

At the top of the casing C, an opening 236 and a conduit 237 communicate from the interior of the casing through a blower 240 to a conduit 35 241. The blower 240 is operated by a motor 242, controlled by a switch 245, to draw air from the casing, and exhaust it through the conduit 241, when it becomes excessively moist, as indicated by a humidostat 246.

40

Operation

In operation, by turning the handle 125, and energizing the motor 121, by pressing the foot switch 128, the speed of the pulley 117 is adjusted in accordance with the stockings to be dried, and the amount of heat required to dry them.

Motion of the pulley 117 is transmitted by the belt 116 to the pulley 115, and from the latter, through the shaft 112, to the worm screw 110. The screw 110 turns the gear wheel 109, which motion is transmitted, through the shaft 102, to the pinion 101. Motion is continued from the latter through the gear wheel 92, thus rotating the turntable 80 and the forms 171 at a speed 55 greatly reduced from the speed of the motor shaft 120.

The main valve 197, and the valves 209 and switches 233 governing the superheater H are adjusted, depending upon the character of the stockings being dried, as to the amount of internal heat required for the forms, and as to whether one or both, or neither, of the superheaters H should be in operation, whereupon, the apparatus is set up for drying.

With the main valve 197 open, steam passes, from the main supply inlet 196, through the valve 197, and the pipes 200, 201 and 140, to the distributor K, from which it passes, as indicated by arrows Y, through the outlets 175 to the tubes 180. From the latter, the steam courses through the tubes 190 and 191, to heat the forms, and back through the tubes 181 to the collector L, as indicated by arrows Z, from which it passes through the tube 147, the T-connector 156, the

thermo-couple tube 157, the strainer 160, and the trap 161, to the drain pipe line 164, upon which a vacuum is impressed to accelerate the fluid action at the exit side of the machine.

With the superheaters H in operation, steam is drawn from the pipe 200 at the T-connector 216, and passes through the T-connector 215 and the pipes 212, to the radiators V, from which it descends, through the pipes 220 and 221, to the T-connector 156 for draining and subjection to the vacuum effect, as above set forth.

With a supply of wet stockings in the compartment 67, the operator stands at the front of the machine, and places these stockings successively on the forms, as the forms pass the mirror 56, the rate of motion of the forms being such that an experienced operator has plenty of time to mount each stocking effectively, glancing at the reflection of the rear side of the form in the mirror, if necessary.

The stockings, thus immediately subject to the internal heat of the forms, then pass through the entrance 50 into the passageway 46, where they are subjected to heat from the forms, the arms 170, the drum E and other parts.

With the superheaters H in operation, warm air is drawn from the space 55 and, as indicated by the arrows A in Figs. 1 and 3, passes outwardly through the conduits 225 to the blowers 227, by which it is impelled through the radiators V. Thus superheated, the air is forced against the passing forms and, as indicated by the arrows B, the superheated air which by-passes the forms, impinges against the curved baffle sections or deflectors 235, by which it is directed along the passageway 46 to the rear of the casing, where it returns, through the passageway 52, to the space 55 from which the warm air was originally drawn.

By having the entrance 50, and the exit 51, as small as practicable, the deflectors 235 for directing the superheated air rearwardly, and by returning the air from the superheater to the space 55, heat is conserved and the speed of operation raised for heavy stockings, and similar conservation of heat is effected by the entrance, exit, casing and baffle elements for stockings of lighter weight.

The direct individual path feeding of the heating medium from the small central distributor to each form, is also a very effective conservator of the internal heat of the forms, as well as a feature enabling the parts to be reduced in number, weight and cost, and conduces to the production of a machine or apparatus that is very effective, and economical in manufacture, shipping, storing, assembly and operation.

The symmetrical repetition of parts, the flat-plane character of the panels and other elements of the casing and baffles, also enable this part of the structure to be packed in small bulk of light weight for storing and shipping, and enable it to be set up, with a minimum of trouble and expense, for effective cooperation with the other elements.

I claim as my invention:

1. In textile fabric drying and shaping apparatus, a support, a form carrier rotatably mounted on said support comprising a hub-like fluid distributor, arms extending radially from said distributor, an annular series of forms disposed one on each of said arms and conduit means supported by each of said arms providing a fluid path from said distributor to the corresponding forms.

2. In textile fabric drying and shaping apparatus, a support, a distributor for a form-heating medium including a member movably mounted on said support, a plurality of arms projecting from said member, a hollow form mounted directly on each of said arms, and means carried by each of said arms for directing said medium from said distributor through the corresponding form.

3. In textile fabric drying and shaping apparatus, a support, means for distributing and collecting a form-heating medium including means movably mounted on said support, a plurality of hollow arms carried by, and projecting from, said movable means each having a continuous extension of the arm length constituting a fabric-receiving hollow form, and means for directing said medium from the distributor into, and along, each of said arms into the corresponding form and from the latter along the same arm to the collector.

4. In textile fabric drying and shaping apparatus, a support, distributing and collecting means for a form-heating fluid rotatably mounted on said support, a plurality of arms extending radially from said support, a hollow form on each of said arms, and conduits carried by each of said arms connected from said distributing means into said forms and from the interior of said forms to said collecting means and constituted both as means for directing said fluid and as means for causing moisture of condensation from said arms and forms to flow to said collecting means.

5. In textile fabric drying and shaping apparatus, a support, and a structure in the form of a spider having a hub-like body rotatably mounted on said support and including distributing and collecting means for a form-heating fluid, a plurality of hollow arms radially disposed symmetrically about said body and detachably connected to said body at the inner ends only whereby upon detachment only at said end each arm may be separated from the spider independently of each other arm, a plurality of hollow forms provided one for each arm detachably connected thereto constituting an extension of the outer end length thereof, and conduit means in the arms and forms providing an individual path along each of said arms for said fluid from said distributing means to the corresponding form and back to said collecting means.

6. In a textile fabric drying and shaping apparatus, a support, a form carrier rotatably mounted on said support comprising a hub-like structure constituting both distributing and collecting means for a form-heating fluid, an annular series of fabric article receiving hollow forms of given number disposed radially outwardly from said hub-like structure in annular spaced series relation to each other, a plurality of hollow arms of corresponding number provided one for, and separate from, each of said forms constituting the sole supporting connection between its individual form and said hub-like structure, sealing means between each arm and form, and conduit means supported in the arms and forms for directing said fluid individually along each of said arms from the distributing means through the corresponding form and back to the collecting means.

7. In textile fabric drying and shaping apparatus, a support, a form carrier rotatably mounted on said support comprising a hub-like structure constituting both distributing and collecting means for a form-heating fluid, said structure being in the form of a single vertical drum hav-

ing a generally horizontal partition intermediate its top and bottom end closure walls dividing the drum into a top distributor chamber and a bottom collector chamber, said partition sloping slightly downwardly toward its center and having a small drain opening from the upper to the lower chamber, a fluid inlet for the distributor chamber, a fluid outlet for the collector chamber, an annular series of fabric article-receiving forms disposed radially outwardly from said hub in annular spaced series relation to each other, and conduit means for directing said fluid from the distributor chamber through the forms and back to the collector chamber.

8. In a fabric forming dryer, a fluid distributor and collector unit, a plurality of arms extending radially from said unit each having a form support at its outer end and longitudinal side portions diverging from the unit parallel to corresponding side portions of adjacent arms at opposite sides thereof to a given position from which they continue and converge to said form support, and conduit means in each arm and form provid-

ing a fluid path from the distributor through the arm into the form in which the path turns and extends from the form through the arm to the collector.

5 9. In textile fabric drying and shaping apparatus, a support, a form carrier rotatably mounted on said support comprising a hub-like structure constituting both distributing and collecting means for a form-heating fluid, said structure being in the form of a single vertical drum having a generally horizontal partition intermediate its top and bottom end closure walls dividing the hub into a top distributor chamber and a bottom collector chamber, said partition 10 having drain aperture means from the upper to the lower chamber, a fluid outlet for the collector chamber, an annular series of fabric article-receiving forms disposed radially outwardly from said hub in annular spaced series relation to each other, and conduit means for directing said fluid from the distributor chamber through the forms and back to the collector chamber.
